UNITED STATES PATENT OFFICE

2,504,710

EVAPORATOR APPARATUS

Charles P. Ludman, Springfield, and Chester F. Hancock, Primos, Pa., assignors to Westinghouse Electric Corporation, East Pittsburgh, Pa., a corporation of Pennsylvania

Application August 18, 1947, Serial No. 769,200

3 Claims. (Cl. 122—382)

1

The invention relates to evaporators of the tubular type wherein the tube bundle is carried on rails at the lower portion of the shell and it has for an object to use rails constructed to provide conduit spaces having nozzles supplied with water from the spaces and discharging such water as agitating jets to aid in removing scale and refuse from the lower portion of the shell.

A more particular object of the invention is to form the rails of angular section so that the flanges thereof may be welded to the shell to form conduit spaces substantially of triangular section.

The foregoing and other objects are effected by the invention as will be apparent from the following description and claims taken in connection with the accompanying drawings, forming a part of this application, in which:

Figure 1 is a longitudinal sectional view of an evaporator incorporating the present improvement;

Figure 2 is a transverse sectional view taken along the line II—II of Figure 1; and

Figure 3 is a diagrammatic and isometric view showing the rails constructed to support the tube bundle and to serve as means for discharging agitating jets of water into the lower portion of the shell.

In the drawing, there is shown a shell, at 10, having a tube bundle, at 11, therein.

The shell comprises a body portion 12 closed at one end by the end wall 14 and at the other end by a detachable cover 15.

The tube bundle, at 11, includes an inlet header 16, a discharge header 17, and a nest of tubes 18.

A conduit 19 supplies water to manifolds 21 arranged in the upper portion of the shell above the tube bundle and the manifolds have nozzles 22 distributed therealong to discharge water as a curtain of spray above the tube bundle. A pipe 23 supplies heating medium, for example, steam to the inlet header 16, a vent connection 24 provides for discharge of air and noncondensable gases from the upper portion of the discharge header 17 and a discharge conduit communicating with the lower portion of the discharge header is arranged to discharge condensate from the latter.

A pair of horizontal rails 26, 26 are carried interiorly by the shell at the lower portion there-

2

of and the headers have bearing relation with respect to the rails, the inlet header 16 being carried by feet 27, 27 which bear on the rails and the discharge header 17 bearing directly thereon, whereby the tubes 18 are inclined downwardly toward the discharge header.

The rails 26, 26 are each of angle section with the flanges 28 and 29 thereof welded to the interior of the shell so as to form conduits 31, 31 closed at the ends by plates 32 and connected by a crosspipe 33 to form a common space to which water is supplied by the pipe 34.

The horizontal flanges 28 of the rails provide supporting surfaces carrying the tube bundle and the vertical flanges 29 thereof have orifices or nozzle openings 35 distributed therealong, supplied with water from the conduit spaces, and from which agitating jets of water discharge into the lower portion of the shell to aid in the discharge of scale and refuse through the bottom discharge opening or openings 36 of the shell.

While the invention has been shown in but one form, it will be obvious to those skilled in the art that it is not so limited, but is susceptible of various changes and modifications without departing from the spirit thereof.

What is claimed is:

1. In an evaporator wherein a shell having bottom discharge openings contains a bundle of tubes supplied interiorly with heating medium to heat water contacting the tubes exteriorly to effect vaporization of the water, a pair of rails carried interiorly of the shell for supporting the tube bundle; at least one of the rails providing a conduit space; means for supplying water under suitable pressure to said conduit space; and nozzle openings formed in the rail provided with the conduit space, supplied with water from the latter, and which are arranged to discharge jets of water into the lower portion of the shell to agitate media therein incident to discharge of such media through said discharge openings.

2. In an evaporator wherein a shell having bottom discharge openings contains a bundle of tubes supplied interiorly with heating medium to heat water contacting the tubes exteriorly to effect vaporization of the water, a pair of rails carried interiorly of the shell for supporting the tube bundle; said rails having their edges joined to the shell to form conduit spaces; means for

supplying water to said conduit spaces; and nozzle openings formed in the rails, supplied with water from the latter, and which are arranged to discharge jets of water into the lower portion of the shell to agitate media therein incident to discharge of such media through said discharge openings.

3. Apparatus as claimed in claim 2 wherein the rails each have horizontal and vertical flanges welded to the shell and the nozzle openings are formed in the vertical flanges and distributed therealong.

CHARLES P. LUDMAN.
CHESTER F. HANCOCK.
